UNITED STATES PATENT OFFICE.

GEORGE B. DAHL, OF WOODHAVEN, NEW YORK, AND THOMAS S. TORRESSON, OF WOODCLIFF, NEW JERSEY.

ASH AND GARBAGE RECEPTACLE.

Application filed March 4, 1922. Serial No. 541,001.

To all whom it may concern:

Be it known that we, GEORGE B. DAHL, a citizen of the United States, and a resident of Woodhaven, in the county of Queens and State of New York, and THOMAS S. TORRESSON, a citizen of the United States, and a resident of Woodcliff, in the county of Bergen and State of New Jersey, have made and invented certain new and useful Improvements 5 in Ash and Garbage Receptacles, of which the following is a specification.

Our invention relates to ash and garbage cans and has for its object to provide a receptacle of this type which is provided with 15 wheels or rollers so mounted that they will be raised slightly above the level of the floor when the receptacle is resting on its base, so that the receptacle when so positioned will possess all the usual inherent stability of the 20 ordinary ash or garbage receptacle, and with the wheels so arranged that when the can is slightly tilted the wheels or rollers will contact with the floor and elevate the base of the can thereabove, rendering the can conveniently portable so that it may be easily moved 25 about.

A further object is to accomplish the aforementioned ends and to so position the rollers that the can may be conveniently 30 dragged up the usual type of cellar steps and with the wheels and rollers not only holding the base of the can above the tread of the stairs but, in addition, holding the body of the can away from the back of the stairs.

35 A further object is to provide a receptacle having permanently secured thereto wheels or rollers so mounted as to be strong and rigid in construction and thus capable of receiving considerable abuse and jars and 40 shocks without causing the rollers to be torn from the receptacle body.

A further object is to provide a structure 45 whereby the ordinary ash can may be conveniently turned into our improved type of portable can and as thus equipped possess all the advantages and characteristic features of our novel and improved receptacle.

A further object is to improve generally 50 and enhance the utility of articles of the class to which the invention relates, and with the foregoing and other objects in view, our in-

vention consists in the improved ash can illustrated in the accompanying drawings and hereinafter described and claimed, and in such variations and modifications thereof 55 as will be obvious to those skilled in the art to which our invention relates, it being understood that changes may be made within the scope of what is claimed without departing from the spirit thereof.

60 The preferred embodiment of our invention is disclosed in the accompanying drawings, wherein:

Figure 1 is a view in side elevation of a 65 receptacle embodying the characteristic features of our invention;

Figure 2 is a similar view showing the receptacle tilted so as to rest solely upon the 70 rollers and thus be rendered conveniently portable;

Figure 3 is a top plan view of the receptacle;

Figure 4 is a developed view of the housing or mounting for each roller;

Figure 5 is an enlarged fragmental view 75 in bottom plan of a portion of the receptacle and showing the roller and mounting therefor secured to the can or receptacle;

Figure 6 is a front elevation of the parts disclosed in Figure 5;

Figure 7 is a top plan view of a modified form of our invention, the portable features being incorporated in an ordinary can by means of an attachment;

Figure 8 is a view in vertical section 85 taken on the line 8—8 of Figure 7;

Figure 9 is a similar view of a somewhat further modified form of our invention, and

Figure 10 is a view in section taken on the line 10—10 of Figure 5.

90 Referring specifically to the several views, wherein similar reference numerals designate corresponding parts throughout, the receptacle 15 is of the usual type for the handling of ashes, garbage, or similar refuse, 95 and is provided with the usual type of reinforcing band 16 at the top and a similar reinforcing band 17 located at the base of the receptacle. The receptacle is also provided with the customary handles 100 18. Rigidly secured to the lower reinforcing band 17 are the two roller supports

19 spaced a suitable distance apart and mounting or supporting the rollers 20. The roller supports are in the nature of a housing and comprise the spaced side walls 21 connecting integral top wall 22 and the rear attaching flanges 23, the latter being provided with suitable holes 24 extending therethrough and through which pass the rivets 25 or other suitable holding means whereby the housing is most rigidly secured to the body of the can adjacent the lower edge thereof. The two housings are spaced apart, and extend substantially at right angles to a diametric line of the base, as illustrated in Figure 3.

Each housing or roller support has a roller 20 mounted therein which, as shown in detail in Figure 10, is supported by the shaft or pivot pin 26, the roller being preferably provided with a bushing 27, so that the roller will readily turn upon its pivotal support and properly support the very considerable weight of the filled can or receptacle thereon. Attention is called to the fact that the roller supports are of box-like formation and being secured to the reinforcing band of the can at spaced points are practically indestructible and thus capable of withstanding the abuse and extreme service to which articles of this class are ordinarily exposed.

The rollers 20, as disclosed in Figure 1, are so positioned that when the receptacle 15 is resting upon its base they will be raised a slight distance above and out of contact with the floor. They are also so positioned that a line joining their lower periphery will pass in front of the periphery of the can body, as clearly illustrated in Figure 3, so that as the can is tilted, as in Figure 2, the rollers will be lowered until such time as they reach and contact with the floor and support the base of the receptacle thereabove and thus render the receptacle conveniently portable. The front edges of the roller supports or housings are curved so as to closely approximate the curvature of the rollers and thus protect the same, and are so positioned with respect to the rollers as to expose the front or forward portion of the rollers, as well as the lower portion. This forward protrusion of the rollers also provides that the can may be easily dragged up the ordinary cellar steps, as the rollers will contact first with the tread of the stairs and then with the rear wall of the stairs.

The housings with their rollers therein are preferably located below and upon opposite sides of one of the handles 18, so that the same force which is applied to tilt the can 60 will, when the rollers contact with the floor, cause the can to be moved therealong, although we do not wish to limit ourselves to this particular arrangement of rollers

with relation to the handles, and in this regard we particularly wish to mention that while we have spoken of the receptacle as being designed for the handling of ashes and garbage, the receptacle may partake of other forms and other uses.

In order that the advantages of my portable receptacle may be incorporated in cans or receptacles already built and in use, we have provided the modified forms of our invention as shown in Figures 7, 8 and 9, 75 and referring particularly to Figure 7 it will be seen that we have provided the housings or roller supports 19' secured to an auxiliary band 17', this band being adapted to completely encompass the lower reinforcing band of the ordinary can and may be drawn tightly thereagainst by providing the ends of the bands 17' with the spaced outstanding ears or lugs 28 and through which extends a clamping bolt 29. This auxiliary 80 band 17' may be provided with the two spaced ledges or inturned edges 30 and 31, as shown in Figure 8, or comprehend the use of a single lower ledge 31', as shown in Figure 9, so that the housings and the carrying auxiliary band may in the one instance be readily applied and secured to a receptacle 32 which has a reinforcing band 33 at its base portion, or on the other hand may be applied to a receptacle 34 which has a 85 flat or continuous side wall unbroken by any reinforcing bands.

Thus the characteristic features of our invention may be incorporated in receptacles of various types and as ordinarily constructed and when equipped with our improvements will possess all of the advantages and features of a can having the parts built directly thereon. The portable features of our device will be readily appreciated by those 100 who are required to not only move the ash cans from the cellar but are further required to place the ash cans on the front sidewalks in order that they may be emptied. Further, the particular form of roller support or 105 housing prevents them from being torn from the receptacle body and the limited protrusion of the roller from the housing provides for their adequate protection.

Having thus described and explained our 115 invention, we claim and desire to secure by Letters Patent:

1. An attachment for receptacles of the class described comprising a housing bent from a single sheet of metal and comprising spaced side walls, an integral top wall and flanges formed integrally with the side walls and bent into the arc of a circle and adapted to be secured to the lower extremity of a receptacle, and a roller mounted between and carried by the said side walls.

2. A device of the class described comprising a casing including top and spaced

side walls, a roller carried by said side walls and extending slightly in front of said top and side walls and protected thereby, the rear extremities of said side walls bent into 5 the arc of a circle and adapted to be secured to a can body.

Signed at New York, borough of Manhattan, in the county of New York and State

of New York, this 3rd day of March, A. D. 1922.

GEORGE B. DAHL.

THOMAS S. TORRESSON.
